UNITED STATES PATENT OFFICE.

GILBERT HENRY DAVIDSON, OF MORENCI, ARIZONA TERRITORY.

ORE-CONCENTRATOR.

No. 893,985.

Specification of Letters Patent.

Patented July 21, 1908.

Application filed February 3, 1908. Serial No. 414,021.

To all whom it may concern:

Be it known that I, GILBERT HENRY DAVIDSON, a citizen of the United States, and a resident of Morenci, in the county of Graham and 5 Territory of Arizona, have invented a new and Improved Ore-Concentrator, of which the following is a full, clear, and exact description.

The invention relates to concentrators in which the material carried on an endless traveling apron is subjected to a stream of water for separating the concentrates and tailings,

The object of the invention is to provide a new and improved ore concentrator, in which 15 the material carried on an endless traveling apron is subjected intermittently to sheets of water, to allow the concentrates to move forward in a sheet undisturbed, to permit the concentrates to pass the impact line of the 20 water undisturbed, the concentrates being washed forward by the water, and the latter being free to flow back smoothly, to produce an effective washing of the onward moving material, and hence the very fine material is 25 not disturbed or washed away with the tailings, thus insuring a complete saving of the concentrates.

The invention consists of novel features and parts and combinations of the same, 30 which will be more fully described herein-after and then pointed out in the claims.

A practical embodiment of the invention is represented in the accompanying drawings forming a part of this specification, in which 35 similar characters of reference indicate corresponding parts in all the views.

Figure 1 is a side elevation of the improvement, parts being in section; Fig. 2 is an enlarged sectional side elevation of the im- 40 provement, and Fig. 3 is a plan view of the same.

The material to be concentrated is distributed by the distributor A, onto the endless apron or belt B, traveling forward in the direction of the arrow a', and under a transversely-extending water trough C, arranged for intermittently discharging its contents onto the material carried forward on the apron or belt B. The trough C normally 45 stands in the water-receiving position shown in the drawings, and tilts periodically forwardly and downwardly, to discharge the water in the form of a transverse sheet onto the material and in the direction in which the 50 material travels with the apron B (see dotted lines in Fig. 2). Now during the time the

trough C is in the filling position mentioned, a portion of the concentrates on the apron B is carried forward practically undisturbed on the apron B, to finally pass beyond the transverse line of discharge or impact of the water on the concentrates, and hence such concentrates which have passed the said transverse line are washed forward on the apron B at the next discharge of the water from the 60 trough C. The water after its discharge onto the rearwardly and downwardly inclined apron B, gently flows down the apron in the inverse direction in which the apron is traveling, so that the water effectively acts on the 65 material to concentrate the heavier particles on the apron and to wash the tailings down the apron and over the lower end thereof to a tailing chute. The concentrates are carried by the apron over the driven apron roller D, 70 to finally drop into the receiver E, the lower run of the apron passing through a wash box F for cleaning the apron.

In order to periodically or intermittently tilt the trough C for the purpose above described, the following arrangement is made: The trough C is approximately V-shape, and its rear side is attached to a block G, provided at its ends with trunnions G' journaled in brackets H, attached to the water supply box 80 or reservoir I, supplied with water by a suitable water supply J, as indicated in Fig. 1. The water box I is supported from the frame of the machine in front of the material distributor A, and the front side of the said 85 water box I is provided with forwardly and downwardly extending overflow chutes I', discharging into the trough C, to fill the same with water from the water box I. To the block G of the trough C is secured a forwardly-extending arm K, connected at L' by a link L with a counterbalancing lever N, pivoted at N' on a bracket O' attached to a suitable support O carried on top of the water box I. On the counterbalancing lever 90 N is adjustably held a weight P by a set screw P', to permit of adjusting the weight P on the lever N, so as to cause the lever N to be over-balanced at the time a desired amount of water has passed into the trough 95 C. In order to allow minute adjustment of the counterbalancing device, the lever N is provided with a row of apertures N², either one of which can be engaged by the pivot pin N', and the link L is similarly provided with 100 a row of apertures L², either one of which is adapted to be engaged by the pivot pin L'.

Now when the machine is running and the material is distributed by the distributor A on the apron B, and the latter travels forward in the direction of the arrow a' , and water in flowing from the water box I into the trough C finally fills the same and overbalances the lever N, then the trough C tilts forwardly and downwardly (see dotted lines in Fig. 2), and the water contained in the trough C is discharged in a transverse sheet onto the material carried forward on the apron or belt B and in the direction in which the apron is traveling. As previously stated, concentrates in front of the line of discharge 15 of the water onto the apron, are washed forward while the water in flowing down the apron washes the material contained thereon, it being understood that after the water is discharged from the apron B, the trough C 20 immediately tilts back to its normal position by the action of the counterbalancing lever N. When this takes place, the trough C is refilled with water from the water box I, and during this time a portion of the concentrates 25 on the apron B is carried forward beyond the line of contact, as previously mentioned.

It is not deemed necessary to describe or illustrate other detail mechanisms of the concentrating machine, such as the driving gear for the apron or the detail construction of the distributor A, as such mechanisms may be of any approved construction, and my improvement may be readily applied to various makes 30 of concentrating machines, and hence I do not limit myself to any particular construction or any special type of concentrating machines.

Having thus described my invention, I claim as new and desire to secure by Letters Patent:

1. An ore concentrator comprising an endless traveling apron inclined upward in the direction of its motion, means for spreading ore on the apron, and means for discharging a transverse sheet of water on to the belt at regular intervals in the direction of movement of the belt, and in front of the spreading means. 40

2. An ore concentrator comprising an endless traveling apron inclined upward in the direction of its motion, and means for discharging water on the belt at regular intervals in the direction of movement of the belt. 50

3. An ore concentrator provided with means for carrying the material forward and upward, and means for periodically discharging a transverse sheet of water on the material in the direction in which the material is traveling. 55

4. An ore concentrator provided with means for carrying the material forward and upward, means for spreading the material on the carrying means, and means for periodically discharging a transverse sheet of water on to the material in the direction of movement of the material. 60

In testimony whereof I have signed my name to this specification in the presence of two subscribing witnesses.

GILBERT HENRY DAVIDSON.
